TUBING APPARATUS

William E. Kanady, Houston, Tex., assignor, by mesne assignments, to Esso Research and Engineering Company, Elizabeth, N. J., a corporation of Delaware

Application October 5, 1955, Serial No. 538,580

14 Claims. (Cl. 166—243)

The present invention is directed to an apparatus for use in a cased and tubed well bore. More particularly, the apparatus is directed to be used on a tubing string which is permanently located in a cased well for extending the length thereof.

The present invention may be briefly described as an apparatus for extending the lower end of a tubing in a well when desired. The apparatus comprises a hydraulic cylinder enclosing a tubular mandrel with the tubular mandrel having an inside diameter at least as large as the inside diameter of the tubing string and connected to the lower end of the tubing string. A tubular extension member is slidably arranged on the tubular mandrel and, upon pressure being applied to the upper end of the hydraulic cylinder by a separate conduit attached thereto and leading to the earth's surface, the tubular extension is forcibly extended out of the bottom of the hydraulic cylinder. The tubular extension member may be retracted by applying pressure through another conduit which is connected to the lower end of the hydraulic cylinder whereby pressure applied therethrough forces the tubular extension to its retracted position. A coil spring, and the like, may also be used to retract the extension member or pressure may be applied to the annulus between the tubing string and the casing and, by providing fluid ports in the lower end of the hydraulic cylinder, the extension member may be biased to its retracted position.

The present apparatus is specifically useful in permanent well completion methods where the lower end of the tubing string is set once in the productive life of the well above a plurality of potentially productive formations, sands, hydrocarbon zones, strata, intervals, and the like from which hydrocarbons such as oil and/or gas are obtained.

The apparatus in its retracted position allows well completing tools, such as a gun perforator, to be lowered through the tubing. The hydraulic cylinder arrangement allows positive extension of the apparatus for such operations as washing out excess cement or sand accumulated in the casing.

Other advantages may be seen by the following description taken in conjunction with the drawings in which:

Fig. 1 is a sectional view of a preferred embodiment of the present invention;

Fig. 2 is an elevational view, partly in section, of another embodiment;

Fig. 3 is a sectional view of still another embodiment.

Referring now to the drawings and particularly to Fig. 1, a casing, such as 10, extends from the earth's surface, not shown, to penetrate a productive formation, such as 11. A tubing string 12 is arranged in the casing with its lower end above the formation 11. It may be understood that the tubing may also be placed above a plurality of productive formations, not shown. Connected to the lower end of the tubing 12 by such means as a collar or coupling 13 is a hydraulic tubing extension as-

2

sembly generally designated by the numeral 14. The assembly consists of an inner tubular mandrel 15, having at least as large a central bore as that of the tubing 12. A sealing means, such as an O ring 16, is arranged in an annular recess 16a about the outer periphery adjacent the lower end of the mandrel 15. Concentrically arranged about the mandrel 15 and fixed thereto by means, such as threaded connection 17, is a cylindrical housing 18. The housing 18 and the mandrel 15 form a pressure chamber 19. The chamber 19 is closed at its upper end by cap member 20 which forms part of the mandrel 15. The housing 18, as shown, extends to the lower end of the mandrel 15. The inner wall of the housing 18 and the outer wall of the mandrel 15 form an annular opening 21 adjacent their lower ends. Sealing means, such as O ring 22, is arranged in an annular groove 22a in the housing 18 adjacent the O ring 16.

Ports 23 are provided in the lower end of the housing 18 and fluidly communicate the chamber 19 with the casing annulus 24.

A conduit 25 is connected into the plate 20 and fluidly communicates with the chamber 19. The conduit 25 extends to the earth's surface and is connected to a source of fluid pressure, not shown.

A tubular extension member 26 provided on its upper end with an annular shoulder or piston 27 is slidably arranged on the mandrel 15. The extension member 26 extends through the annular opening 21 and sealingly engages O rings 16 and 22.

A fluid seal is afforded between the outer periphery of the annular shoulder 27 and the inner wall of the housing 18 by O rings 28 arranged on annular shoulder 27.

Latching means, such as latch springs 29, are fixed to the mandrel 15 adjacent the upper end of chamber 19. A latching ring 30 is fixed to the upper end of mandrel 15 for latching engagement with latch springs 29 when member 26 is in its fully retracted position.

As shown in Fig. 1, the casing 10 has been previously perforated as at 31 by a suitable perforator, not shown, which may be a mechanical perforator or a bullet gun or shaped charge perforator which has been lowered through the tubing 12 and the assembly 14. The extension member 26 may, at that time, have been in its retracted position. However, the member 26 may be in its extended position and have a perforator lowered through it.

Fig. 1 shows the extension member in its fully extended position and, as an example, is shown being used to wash out by reverse circulation a bed of sand which accumulated adjacent the perforations 31.

When it is desired to extend the member 26, pressure is applied through the conduit 25 to the upper end of chamber 19 above the shoulder 27 of the member 26. This pressure overcomes the latch springs 29 which are at that time engaged in the latch ring 30 and pushes the member 26 downwardly. Fluid accumulated in the chamber 19 below the shoulder 27 is expelled through the ports 23.

Pressure is maintained in the conduit 25 until the operation to be performed, such as washing out sand or cement or spotting cement, acidizing, fracturing, perforating, and the like, is completed. Pressure is then relieved in conduit 25 and pressure is applied to the casing annulus 24 whereby fluid pressure is applied to the underside of shoulder 27 by way of ports 23 and the member is pushed back to its retracted position until latch ring 30 engages with latch springs 29.

Referring to Fig. 2, the embodiment is similar to the device in Fig. 1, excepting the fluid ports 23 of Fig. 1 have been replaced with a threaded inlet 32 to which is connected a conduit 33 which extends to the earth's sur-

face and is connected to a source of fluid pressure, not shown. The parts of Fig. 2 which are identical to Fig. 1 carry corresponding reference numerals. The extension member 26, as in Fig. 1, is also extended by pressurizing conduit 25 and is retracted by pressurizing conduit 33. The embodiment of Fig. 3 is also similar to Fig. 1 and corresponding parts will also carry corresponding reference numerals; the embodiment of Fig. 3, instead of being pressurized to the retracted position, is retracted by a helical coil spring 34 as shown which has one end biasing against the underside of annular shoulder 27 and its other end biasing against the lower end of housing 18. The embodiment of Fig. 3 requires no latching means as in Figs. 1 and 2.

The present invention as illustrated and described affords a tubing extension apparatus which can be positively extended and retracted.

The invention is, therefore, quite advantageous and useful. The length of a tubing may be extended or varied without requiring use of any tools. The extended tubing or tubing of varied length has a full opening bore through which well tools, such as wire line perforators and the like, may be lowered.

Having fully illustrated and described the present invention and its operation, what I claim is:

1. Apparatus for extending the lower end of a string of tubing placed in a well bore comprising, in combination, a housing concentrically arranged about and connected to the lower end of said tubing, a tubular extension member slidably arranged in said housing in fluid sealing engagement therewith, means connected to said housing for extending said tubular extension member from said housing, means in said housing for retracting said tubular extension member and means for releasably latching said tubular extension member in its fully retracted position.

2. Apparatus in accordance with claim 1 in which the means for retracting said tubular extension member is a helical coil spring.

3. Apparatus in accordance with claim 1 in which the means for extending said tubular extension member is a fluid pressure conduit connected into the upper end of said housing.

4. Apparatus for extending the lower end of a string of tubing placed in a well bore comprising, in combination, a tubular mandrel concentrically connected to the lower end of said tubing, a housing concentrically spaced about and connected to said tubular mandrel, a tubular extension member slidably arranged on said mandrel in said housing, pressure means connected to said housing for extending said tubular extension member through the lower end of said housing, means connected to said housing for retracting said tubular extension member, and means for releasably latching said tubular extension member in its fully retracted position.

5. Apparatus in accordance with claim 4 in which the means for extending said tubular extension member is a fluid pressure conduit connected into the upper end of said housing.

6. Apparatus in accordance with claim 4 in which the means for retracting the tubular extension member is a fluid pressure conduit connected to the lower end of said housing.

7. Apparatus for extending the lower end of a string of tubing placed in a well bore, comprising, in combination, a tubular mandrel coaxially connected to the lower end of said tubing, said mandrel having a central bore

therethrough at least as large as the central bore of said tubing, a housing concentrically arranged about and connected to said tubular mandrel, a tubular extension member slidably arranged in said housing and on said tubular mandrel for operably extending through the lower end of said housing, pressure means connected to said housing for extending said tubular extension member, means in said housing for retracting said tubular extension member and means for releasably latching said tubular extension member in its fully retracted position.

8. Apparatus in accordance with claim 7 in which the means for retracting said tubular extension member is a helical coil spring.

9. Apparatus for extending the lower end of a string of tubing placed in a well bore, comprising in combination, a tubular mandrel coaxially connected to the lower end of said tubing, said mandrel having a central bore therethrough at least as large as the central bore of said tubing, a housing concentrically arranged about and connected to said tubular mandrel, a tubular extension member slidably arranged in said housing and on said tubular mandrel for operably extending through the lower end of said housing, said tubular extension being provided with a piston head on its upper end, pressure means connected to said housing for extending said tubular extension member, means arranged in said housing for retracting said tubular extension, and means in said housing for releasably latching said tubular extension member in its fully retracted position.

10. Apparatus in accordance with claim 9 in which the means for retracting said tubular extension member is a helical coil spring.

11. Apparatus in accordance with claim 9 in which the means for retracting said tubular extension member is a pressure conduit connected into the lower end of said housing.

12. Apparatus for extending the lower end of a string of tubing placed in a well bore comprising in combination, a tubular mandrel coaxially connected to the lower end of said tubing, a housing arranged about and connected to said tubular mandrel, a tubular extension member slidably arranged in said housing and on said tubular mandrel for operably extending through the lower end of said housing, a piston head provided on the upper end of said tubular extension member, pressure means connected into the upper end of said housing for extending said tubular extension member, pressure means provided in the lower end of said housing for retracting said tubular extension member and means in said housing for releasably latching said tubular extension member in its fully retracted position.

13. Apparatus in accordance with claim 12 in which the means for retracting said tubular extension member is a helical coil spring.

14. Apparatus in accordance with claim 12 in which the means for retracting said tubular extension member is a pressure conduit connected into the lower end of said housing.
